FACE GUARD FOR A HELMET

Dennis L. Burns, 4512 6th Ave. NW,
Seattle, Wash. 98107

Filed Mar. 9, 1966, Ser. No. 1,365

Term of patent 14 years

(Cl. D2—233)

FIG. 1

FIGURE 1 is a front elevational view of a face guard for a helmet showing my new design, the broken line showing of a helmet being for purposes of illustration only;

I claim:

The ornamental design for a face guard for a helmet, substantially as shown and described.
